United States Patent Office

Des. 183,945
Patented Nov. 18, 1958

183,945

MINERAL CAR

Charles Vernon Osborne, Wise, Va.

Application May 15, 1958, Serial No. 50,898

Term of patent 7 years

(Cl. D66—1)

FIG.2

Figure 1 is a perspective view of a mineral car embodying my new design, the side not disclosed being substantially the same as that shown; and

Figure 2 is a rear perspective view thereof.

I claim:

The ornamental design for a mineral car, as shown and described.
